CLAIM

The ornamental design for a mounting device as shown and described.

DESCRIPTION

FIG. 1 is a front top perspective view of a first embodiment of a mounting device showing my new design;

FIG. 2 is a rear bottom perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a front top perspective view of a second embodiment of a mounting device showing my new design;

FIG. 10 is a rear bottom perspective view of the mounting device of FIG. 9;

FIG. 11 is a front elevation view of the mounting device of FIG. 9;

FIG. 12 is a rear elevation view of the mounting device of FIG. 9;

FIG. 13 is a right elevation view of the mounting device of FIG. 9;

FIG. 14 is a left elevation view of the mounting device of FIG. 9;

FIG. 15 is a top plan view of the mounting device of FIG. 9; and,

FIG. 16 is a bottom plan view of the mounting device of FIG. 9.

The broken lines depict portions of the mounting device in which the design is embodied that are not considered part of the claimed design.
